UNITED STATES PATENT OFFICE.

SAMUEL A. CHAPMAN, OF WATERBURY, CONN., ASSIGNOR TO THE CHAPMAN & ARMSTRONG MANUFACTURING COMPANY, OF SAME PLACE.

CURTAIN LOOP OR HOLDER.

SPECIFICATION forming part of Letters Patent No. 287,234, dated October 23, 1883.

Application filed September 10, 1883. (No model.)

To all whom it may concern:

Be it known that I, SAMUEL A. CHAPMAN, a citizen of the United States, residing at Waterbury, in the county of New Haven and State 5 of Connecticut, have invented certain new and useful Improvements in Curtain Loops or Holders; and I do hereby declare the following to be a full, clear, and exact description of the invention, such as will enable others skilled 10 in the art to which it appertains to make and use the same.

My invention relates to loops or holders for curtains, portieres, &c., and has for its object to produce a loop or holder which shall be 15 novel and attractive in appearance, shall be elastic, and at the same time shall be simple in construction and economical in cost.

With these ends in view my invention consists, broadly, in a loop or holder made of coils 20 of wire twisted or braided together in any suitable manner.

My invention also consists in various details of construction, which will be hereinafter fully described, and then specifically designated by 25 the claims.

For the purpose of enabling others to understand and use my improvement, I will proceed to describe the same, referring by letters to the accompanying drawings, in which—

30 Figure 1 is a view of a completed loop or holder. Fig. 2 is a detail view, showing the manner of securing the ends of the coils of wire, and of connecting them to the bells, rings, or other ornaments which complete the 35 device. Fig. 3 is a detail view, in which one of the coils of wire is slightly distended, showing a central wire or cord within the coil, the purpose of which is to prevent undue distension of the coils. Figs. 4 and 5 are views illustrating other patterns, which may be easily 40 made by varying the number and arrangement of the coils or strands.

Similar letters indicate like parts in all the figures of the drawings.

45 A. A represent strands, which consist of coils of wire.

B is a central wire or cord, which lies loosely within certain of the coils. (See Fig. 3.) The object of this central wire or cord is to pre-

vent undue distention of the coils in use. It 50 may or may not be used in all of the coils, but is preferably used in at least two of them, for the reason specified above. The wire composing the coils, at the ends thereof, is bent into the form of loops or rings C, which are 55 caught over a hook, D. The end of the hook is then bent up against the shank, which prevents the coils from slipping off. (See Fig. 2.) A cap, E, perforated at the center, is then slipped over the shank, the end of which is 60 then bent to form a ring or loop, F, (see Fig. 1,) through which other rings or loops are passed, and which securely holds the cap in place, thus concealing hook D and the ends of 65 the coils.

G are rings, and H are ornaments, which are connected together in the manner described above. Any desirable number of these rings and ornaments may be used. The shape or design, also, of the ornaments is not of the 70 essence of my invention, and may be varied without limit without departing from the spirit of my invention. In the present instance I have shown an oval-shaped ornament, a ball, and an acorn. Any or all of these ornaments 75 may, if desired, be bells.

I do not desire to limit myself to any particular number of strands or coils, or to any special arrangement thereof, as they may be braided or twisted, singly or in pairs, in numerous ornamental designs.

The coils may be of any suitable size, and may be made flat, oval, or of any shape. The elasticity and amount of distention of the completed loops are matters within the judgment of the manufacturer. The amount of distention to be allowed is of course regulated by the looseness of the central wire, B.

Any kind of wire may be used; but ordinary brass wire is preferable.

In practice I nickel, gild, and ornament the coils in any well-known manner.

Having thus described my invention, what I claim is—

1. As a new manufacture, a loop or holder 95 for curtains and portieres, consisting of coils of wire braided or twisted together.
2. A loop or holder for curtains, consisting

of coils of wire twisted or braided together, in combination with a hook to which the coils are connected, and a cap covering the hook and the ends of the coils.

- 5 3. In a loop or holder for curtains, coils of wire, two or more of which are provided with a wire or cord lying loosely within the coil, in combination with a hook to which the coils are attached, and a cap covering the hook and
10 the ends of the coils.
4. The combination, with coils of wire, and

hooks to which the ends of the coils are attached, of caps E, which cover the ends of the coils, rings F and G, and ornaments H, all connected together as described.

15

In testimony whereof I affix my signature in presence of two witnesses.

SAMUEL A. CHAPMAN.
